LADDER

Noël L. Dahlander, New Milford, Pa., assignor of
one-half to Robert J. Earl, New Canaan, Conn.

Application August 31, 1943, Serial No. 500,603

5 Claims. (Cl. 223—40)

This invention relates to ladders in general and more especially to pilots' ladders and the like.

Among the objects of the present invention it is aimed to provide an improved ladder suitable for use as a pilot's ladder or the like, characterized by flexible longitudinally extending stiles or suspensory members, broad tread rigid rungs, and clips for connecting the rungs to the suspensory members and for spacing the ladder and particularly the rungs from the side of the structure along which the ladder is used.

It is still another object of the present invention to provide an improved ladder suitable for use as a pilot's ladder or the like, characterized by flexible longitudinally extending strands or suspensory members, broad tread rungs composed of a plurality of rigid rungs, spacers for spacing the ladder, and particularly the rungs from the side of the structure along which the ladder is being used and connecting means for connecting the spacers and rungs to the suspensory members, all in the interest of producing a ladder which can be expeditiously packed up into a comparatively small space when not in use and which can in turn be expeditiously unwrapped and swung over the side of a vessel or the like in the case of an emergency, and which will stand up under the excessive wear and tear to which it may be subjected in case of an explosion or the like.

These and other features, capabilities and advantages of the invention will appear from the subjoined detail description of one specific embodiment thereof illustrated in the accompanying drawing in which

Figure 1 is a plan view.

Fig. 2 is a side elevation partly broken away and partly in section.

Fig. 3 is a section on the line 3—3 of Fig. 2.

Fig. 4 is an enlarged section of one of the clips.

Fig. 5 is a section on the line 5—5 of Fig. 4.

Fig. 6 is a section on the line 6—6 of Fig. 3.

In the embodiment shown the stiles, suspensory members or strands 1, 1 are illustrated as composed of chain links 2, preferably composed of the "lock link" type, having parallel loops 3, 3 at one end, the upper ends of their shanks 4, 4 connected with the main loop 5 of the next adjacent or next succeeding link 2.

The uppermost links 2, 2 of the stiles 1, 1, respectively, are preferably connected as shown to inverted links 6, 6 by rivets 7 extending through parallel loops 3, 3 of adjacent links 2 and 6. The links 6, 6 are provided with shields 8 to form

wearing surfaces for the lash receiving rings 9.

Between the rings 9, 9 of the stiles 1, 1, respectively, and the first rung 10, there are preferably provided a plurality of links 2. In the present instance, and as indicative of good practice, there are shown eight links in each stile 1, including the link 6, although the number of course can vary according to the duty to be performed without departing from the general spirit of the invention.

The rungs 10 are formed to provide a broad tread in the interest of serving a substantial support for the user, and in turn, due to the violent use to which these ladders may be subjected, each rung 10 in the present instance is composed of a plurality of tread members, two sections 11, 11 for each rung being shown so that should one section 11 be injured or destroyed, the other section 11 may serve alone.

20 In the present instance these sections 11 are shown as composed of wood and having their corners beveled or chamfered in the interest of protecting the hands of the user from unduly sharp corners.

25 At the ends of each rung 10 there are provided the spacers or spacing elements 12 composed in the present instance of metal oval dish-shaped disks having inwardly turned or rolled edge portions or rims 13, preferably of greater thickness

30 than the average thickness of the face portions 14 of the disks 12 and the disks 12 also have in the present instance inwardly turned flanges or ears 15, each disk 12 having two sets of pairs, each pair being provided to engage the end of a 35 rung. Preferably as shown, if the thickness of the disk 12 proper is one-eighth of an inch, then one of the ears 15 of a pair has welded thereto a reinforcing plate or strip 16 so that such reinforced ear 15 with its reinforcing plate 16 may be tapped to receive the screws 17. In the present instance each pair of ears has a pair of screws 17 passing down through the upper ear, then through the gripped end of the section 11 and screw-threadedly connected to the lower reinforced ear 15 and thereupon upset.

40 The disks 12 also have outwardly pressed ribs or grooves 18, 19 and 20 with the edge 13 adjacent the grooves 18 and 20 interrupted and bent outwardly as particularly shown in Fig. 4, the 45 grooves 18, 19 and 20 being formed wide enough to receive and clear the links 2 of the stiles 1.

45 Preferably as shown, two links of each stile are attached to each disk 12. As an instance, the link 2 adjacent the upper narrow portion of the disk 12 is provided with a clip 21 having a pair of

yokes 22 to receive the shanks 4, 4 of such link 2 and the intermediate portion of the clip 21 adapted to receive a screw 23 passing through an opening in the disk 12 between the ribs 18 and 19, the screw 23 being screw-threadedly connected to the clip 21 and upset at its projecting end as shown in Fig. 6. Preferably also, as shown, the link 2 disposed adjacent the lower narrow portion of the disk 12 is screw threaded by a similar clip 24.

Preferably as shown, in the interest of good practice, there are provided seven links between each two successive rungs 10, although this number of course can be varied without departing from the general spirit of the invention.

Preferably as shown, the two sections 11 of each rung 10 are spaced apart sufficiently not only to clear the stiles 1, but also to enable the user, often provided with heavy gloves, to grasp the outermost section 11 and at the same time stick his fingers between the two sections 11 of a rung.

Preferably as shown, the width of the disk 12 from the innermost section 11 to the side of the structure with which it is being used is sufficient to enable the user, either to grasp the innermost section if necessary without danger of injury, or to prevent the toe of his shoe or boot being caught in such space.

In actual use excellent results have been achieved when the dimensions of these disks are about five inches wide in a transverse direction and eight and one-fourth inches long in a longitudinal direction.

Preferably also, to protect the user from injury that might arise from engaging the metal of the chains in extreme temperatures, these chains are covered with flexible boots 25 composed of fabric, plastic, or the like. These boots 25 are in the form of flexible tubes as shown, which are slipped over the chains before they are connected to the rungs and then secured in place by the clips 22 and 24 engaging the ends thereof and clamping them in place as shown. The upper ends of the uppermost boots 25 are secured to the links 6 by any suitable means such as the grommets 26.

It is obvious that various changes and modifications may be made to the details of construction without departing from the general spirit of the invention as set forth in the appended claims.

I claim:

1. A ladder having flexible suspensory members composed of chain links, rungs composed of a plurality of wood sections, the sections of each rung spaced from one another in a transverse direction, metal spacing disks for spacing the ladder from the structure with which it is being used having an imperforate medial area, ears pressed out of said disks to either side of said medial area and secured to the ends of said rungs, and means for connecting said suspensory members to said disks along said medial area intermediate said rungs, the outer faces of said disks and the outer faces of said suspensory members

being in substantial alignment with one another to reduce obstructions to a minimum.

2. A ladder having flexible suspensory members, rungs composed of a plurality of sections, the sections of each rung spaced from one another in a transverse direction, metal spacing disks for spacing the ladder from the structure with which it is being used having an imperforate medial area, flanges extending from said disks and connected to said rungs to either side of said medial area, clips for connecting said suspensory members to said disks along said medial area, said flexible suspensory members composed of chain links, and flexible non-metallic boots enclosing said chains, said clips engaging the ends of said boots to secure them in place, the outer faces of said disks and the outer faces of said boots being in substantial alignment with one another to reduce obstructions to a minimum.

3. A ladder having flexible suspensory members composed of chain links, rungs composed of a plurality of wood sections, the sections of each rung spaced from one another in a transverse direction, metal spacing disks for spacing the ladder from the structure with which it is being used, ears pressed from said disks to either side of a medial imperforate area, screws extending through each pair of ears and the end of a rung section and screw-threadedly connected to one of said ears with the ends of said screws upset, clips, and screws for extending through the upper and lower ends of the medial imperforate areas of said disks, through said chains and through said clips and screw-threadedly connected to said clips with their ends upset to anchor said chains to extend along said medial imperforate areas between pairs of rung sections, the outer faces of said disks and the outer faces of said suspensory members being in substantial alignment with one another to reduce obstructions to a minimum.

4. A ladder having flexible suspensory members, rungs composed of a plurality of sections, the sections of each rung spaced from one another in a transverse direction, metal spacing disks for spacing the ladder from the structure with which it is being used, said rungs being connected to said spacing disks, clips for connecting said disks to said suspensory members, said disks being oblong, having inwardly turned rolled edges, and ribs pressed outwardly to clear said chains, the ribs alining with the longitudinal axes of said disks.

5. A ladder having flexible suspensory members, rungs composed of a plurality of sections, the sections of each rung spaced from one another in a transverse direction, metal spacing disks for spacing the ladder from the structure with which it is being used, said rungs being connected to said spacing disks, and clips for connecting said disks to said suspensory members, said disks having ribs pressed outwardly to clear said chains, the ribs alining with the longitudinal axes of said disks.

NOËL L. DAHLANDER.
